UNITED STATES PATENT OFFICE.

DANIEL HOYT, OF EAST ORANGE, NEW JERSEY, ASSIGNOR OF ONE-HALF TO THE NATIONAL LOCK WASHER COMPANY, OF NEWARK, NEW JERSEY, A CORPORATION OF NEW JERSEY.

WEATHER-STRIPPING.

1,157,872.

Specification of Letters Patent. Patented Oct. 26, 1915.

Application filed January 16, 1915. Serial No. 2,610.

To all whom it may concern:

Be it known that I, DANIEL HOYT, a citizen of the United States, residing at East Orange, Essex county, State of New Jersey, 5 have invented certain new and useful Improvements in Weather-Stripping; and I do declare the following to be a full, clear, and exact description of the invention, such as will enable others skilled in the art to which 10 it appertains to make and use the same.

My invention relates to weather stripping means for sealing the side edges of windows and particularly car windows where the cars are constructed of steel and where it is 15 difficult to secure any kind of device to the metallic window frames.

The window frames of the ordinary steel car have metallic side posts to which the outside sash stops are permanently riveted. 20 The inside stops and curtain fixture grooves are usually formed together from a single sheet of metal and are secured to the metallic posts of the window frame with machine screws, and stops are secured to the posts 25 absolutely parallel to the outside stops leaving a space, or sash guideway, therebetween, of somewhat greater width than the thickness of the sash. The side posts, while supposed to be parallel to each other, are found 30 to vary somewhat. With these permanent, unchangeable conditions of the window frame and sash stops, it has been found difficult to prevent the sash from rattling, to stop the passage of air and dust, and to prevent cinders and grit from accumulating in 35 the sash guideways which prevent the proper operation of the sash.

One of the objects of this invention is to so equip a car window sash that it will be 40 air, dust and cinder proof, and yet allow the sash to be readily raised or lowered.

Another object is to make a weather strip which may be readily applied to the flat side edges of a window sash without cutting or 45 grooving and which any ordinary workman can apply without special tools or machinery.

Another object is to make a weather strip partly of felt so that the edges only will 50 contact with the inside and outside sash stops, also to provide means to prevent the

felt contacting the faces of the window posts.

Another object is to equip a sash so that the side edges are weather proof and at the same time are held resiliently between the 55 window posts.

The invention consists of a device as hereinafter described and illustrated in the accompanying drawings, in which:

Figure 1 illustrates a broken portion of a window frame and a sash equipped with the preferred construction of my novel weather strip, the inside sash stops being broken away showing one edge of the felt as it 60 bears on the sash stop, also showing a portion of the guide springs and plates as they bear against the posts of the window frame. The felt is also broken away at one place showing the binders which hold the felt. 65 Fig. 2 shows a cross sectional view of Fig. 1 taken on the line 2—2. Fig. 3 shows a cross sectional view of Fig. 1 taken on the line 3—3. Fig. 4 shows a detail face view of 70 my novel weather strip equipped with 75 spring guides. Fig. 5 is an edge view of Fig. 4. Fig. 6 shows a detail face view of the weather strip having solid guide plates. Fig. 7 is an edge view of Fig. 6. Fig. 8 is a cross sectional view of one side of a sash 80 with a modified form of the weather strip applied to the sash before the latter is installed in the window frame. Fig. 9 is a view similar to Fig. 1, but showing my improvement utilized in connection with guide 85 plates alone at each side edge of the sash. Fig. 10 is a broken section at the line 10—10 of Fig. 6, and Fig. 11 a broken section at the line 11—11 of Fig. 4.

Similar numerals of reference denote like 90 parts in the several figures of the drawing.

Referring to the drawings, 1 is the window sill, 2 are the metallic side posts of the window frame, 3 is the movable sash, 4 the inside sash stops, and 5 the outside sash 95 stops.

In carrying out my invention, I take a strip of thick felt cut with parallel sides, and of a width somewhat wider than the distance between the inside sash stop 4 100 and the outside sash stop 5, the length to be the full length of the sash 3. The felt

is secured between the two metallic binders 6 and 7, the edge 8 of the felt extending considerably more over the edge of the binders 6 and 7 than the edge 9.

5 In applying the strips to the flat side edges of the sash, the metallic binders 6 and 7 are designed to be secured central of the side edges of the sash 3, so that the edge of the felt 9 will be approximately even with the outside face of the sash, or it may extend slightly beyond. The inside edge of the felt 8 extends a considerable distance beyond the inside face of the sash. It will be understood that each side edge of the sash is 10 equipped with one of these weather strips.

On the outside of the binder 7 I secure a series of two or more flat bow springs 10, and these springs may be on both side edges of the sash, or I can locate them on one 20 side edge and equip the other side edge with two or more solid guide plates 14, as shown at Fig. 1. But this is a very immaterial matter and has nothing to do with the weather stripping proper, and, in cheap 25 structures, I can omit the springs altogether, and secure solid guide strips 14 to both side edges of the sash, as shown at Fig. 9. The sash is then placed in the window frame between the posts, the inside 30 stops being removed, and in placing the sash in the window frame the springs are compressed and bear on the faces of the posts holding the sash resiliently between the posts. The sash is then carried back 35 against the outside stops, and the inside stops are placed against the extended portion of the felt 8 and forced back to their position on the post and secured there by means of the screws 15 driven into their 40 previously prepared screw holes. In forcing the inside stops 4 back against the felt edge 8 the outside face of the sash 3 and the felt edge 9 are pressed together against the outside stop 5, thus making practically 45 a packed joint between the inside and outside sash stops. It will be readily seen that, no matter how poorly the sash itself fits in the guideways, either edgewise or 50 sidewise, my improvement attached to the side edges of the sash will render the latter perfectly air tight, will prevent all rattle, and allow the sash to be operated freely.

It will be noted, by referring to Figs. 2 and 3, that the binders 6 and 7 are of a 55 width considerably less than the thickness of the sash, thus leaving recesses 11 and 12 at each side of the felt and between the edges of the binders 6 and 7 and the stops 4 and 5, the use and necessity of which recesses I will now describe.

In forcing the inside stop in position, the felt edge 8 is compressed, and this material, like all other material of an elastic nature, when pressed one way must go another way, and the recesses 11 and 12 are

provided to allow room for the felt to go sidewise when compressed edgewise, and the felt being of an elastic nature tends to resume its former normal shape making a constant pressure on the parallel stops 4 70 and 5. If, in the course of time, the felt becomes "set" in its compressed position, it will still make a perfect molded fit between the inside and outside sash stops, and wear on the edges of the felt against the smooth 75 surfaces of the stops 4 and 5 would be infinitesimal. Also, these spaces 11 and 12 provide pockets extending the entire length of the sash, and if any particles of dirt should work their way into these pockets, 80 such dirt would be deposited on the window sill and could never work its way through the outside and inside felt and into the car.

When solid guide plates 14 are employed they may be made integral with the outer 85 binders 7, if desired, the function of these plates being to prevent the felt from bearing against the rough faces of the posts. Also, the side edges of the sash throughout their length may be so constructed as to 90 form an integral tongue 16 to take the place of the binder 6, as shown at Fig. 8 and I therefore do not wish to be limited in this respect.

While I have used the word "felt" 95 throughout this specification, I want it to be understood that in the place of felt any material of similar nature may be used.

Having thus described my invention what 1 claim as new and desire to secure by Letters Patent is:—

1. The combination of a window frame, said frame having side posts carrying inside and outside sash stops forming guideways for a sash, a sash of less thickness 105 than the width of said guideways and adapted to move therein, a weather strip secured to each side edge of said sash comprising a strip of thick felt made wider than the guideways, said felt having a free edge at each side thereof, one edge adapted to bear against the inside stop and the other edge adapted to bear against the outside stop, the free edges of the felt being compressed between the stops, recesses 110 formed at the sides of the free edges of the felt whereby the felt may have space to expand sidewise into the recesses when compressed edgewise by the stops and thereby prevent the felt from becoming interposed 115 between the faces of the sash and the stops.

2. The combination of a window frame, said frame having side posts carrying inside and outside sash stops forming guideways, a sash adapted to move in the guideways, and a weather strip secured to each side edge of the sash, said weather strip comprising a strip of thick felt wider than the guideways, one edge of the felt extending slightly beyond the outside face of the sash 120

and the other edge of the felt extending a much greater distance beyond the inside face of the sash, the arrangement being such that when the felt is compressed between the 5 stops the force will carry the sash laterally against the outside stops and leave a space between the sash and inside stops.

In testimony whereof I affix my signature in presence of two witnesses.

DANIEL HOYT.
